UNITED STATES PATENT OFFICE

2,573,147

INTERMEDIATE SUPPORT FOR VENETIAN
BLIND TILT RAILS

Bela B. Junkunc, Chicago, Ill., assignor to Bela B. Junkunc, Alexander Junkunc, Sr., Alexander Junkunc, Jr., and Joseph G. Junkunc, doing business as J. & J. Tool & Machine Co., Chicago, Ill., a partnership

Application June 16, 1949, Serial No. 99,523

2 Claims. (Cl. 160—177)

1

This invention relates to an intermediate support for a Venetian blind tilt rail, and is particularly concerned with means for holding a supporting chain against slipping.

Venetian blinds include a tilt rail supported at its ends by some conventional supporting means that will permit the rail to be tilted in either direction. Generally this end support is sufficient, but sometimes, when blinds are substantially wider than the usual single window width, some form of intermediate support is usually required to keep the blind from sagging at its center.

In accordance with the present invention an intermediate support is provided that may be positioned on the tilt rail wherever desired with very little trouble, and will always stay in the position in which it is originally placed. The intermediate support does not interfere with the normal operation of the Venetian blind and is extremely durable in use. It is not necessary to make any changes in a conventional tilt rail in order to secure the intermediate support to it and hence the rail is not weakened in any respect, as in the case of some prior art structures. In fact, the rail is actually strengthened by the intermediate support at the region where it is secured to the rail. This is of especial value where the tilt rail consists of a hollow tubular member.

The structure by which the above advantages are attained will be described in the following specification, taken in conjunction with the accompanying drawing of the preferred illustrative embodiment of the invention, in which:

Figure 1 is a fragmentary front elevation of a Venetian blind embodying my invention mounted in a window frame;

Fig. 2 is an enlarged fragmentary perspective view of the tilt rail shown in Fig. 1, showing in greater detail the manner in which the intermediate support is secured to the tilt rail and mounted on the underside of the top surface of a window frame;

Fig. 3 is a view similar to Fig. 2, showing the roller of the intermediate support mounted on the front edge of a window frame;

Fig. 4 is a detail perspective view of the roller of the intermediate support; and

Fig. 5 is a detail perspective view of the clamp of the intermediate support, which holds the chain or cord extending around the roller in position around the tilt rail.

In the drawings, the reference numeral 2 indicates the sides of a window frame on which the operating ends of a Venetian blind tilt rail

are supported. This rail may be a solid rail of wood, for example, or it may be a hollow rail. The rail shown in the drawings is a hollow rail having a generally rectangular cross-section, but it may have any other desired shape. The Venetian blind structure shown in the drawings is conventional and will not be described in detail. In general, it comprises a plurality of slats 4 and tapes 5, and tilting mechanism 6 and raising and lowering mechanism 7 secured to the opposite ends of the tilt rail.

An L-shaped bracket 8 is mounted on either the underside 9 of the top surface of the window frame, as shown in Figs. 1 and 2, or on the front surface 10, as shown in Fig. 3, at approximately the region where it is desired to support the tilt rail. In either case a roller 11, mounted on the free end of bracket 8, is positioned just above the tilt rail and is adapted to rotate in a plane transverse of the tilt rail.

A chain or cord 12 extending around roller 11 and seated in a circumferential groove 13 has its ends secured to a clamp 14 which is snapped over the tilt rail in the area to be provided with intermediate support. The clamp, suitably made of spring steel or of plastic material, comprises a substantially flat plate 15 and a pair of legs 16. Plate 15 has a length approximately equal to the width of the tilt rail and is positioned adjacent the bottom of the rail. Legs 16 project upwardly adjacent the front and rear walls of the tilt rail and fit snugly thereagainst so that the clamp will remain in any desired position because of the frictional contact between the clamp and the bottom and front and rear walls of the tilt rail. Legs 16 extend upwardly a short distance above the top of the tilt rail, and are recessed, as indicated at 18, to furnish guiding support for the chain or cord as the rail is tilted.

The center portion of plate 15 is cut out and two pairs of ears 17 are formed by striking the metal adjacent the cut out upwardly. The ears of each pair are spaced apart a slight distance so that the ends of the chain, which are preferably enlarged slightly, may each be fixed between the ears of one pair and be retained therein. Ears 17 are spaced from plate 15 a sufficient distance to provide adequate clearance for the end of the chain to be held between the ears and the adjacent bottom wall of the tilt rail. Although it is preferred to use a chain for the intermediate support, any suitable cord or band may be substituted provided the ends are knotted or enlarged in any other suitable manner so that they may be retained between ears 17.

Bracket 8 may be positioned wherever desired,

and then clamp 14 is snapped on tilt rail 3 in the region beneath the bracket. If the clamp does not line up accurately with roller 11, the clamp may be slid laterally of the tilt rail until it is properly aligned. When roller 11 and clamp 14 are aligned, the chain has its opposite ends secured between ears 17 and its intermediate portion positioned in circumferential groove 13. The tilt rail may then be tilted in either direction, and the chain will merely roll along in the groove of roller 11. Recesses 18 in the legs of clamp 14 are in the same vertical plane as the circumferential groove 13 in roller 11 and the openings between each pair of ears 17, so that the chain always moves in the same plane.

Although I have described a preferred embodiment of my invention in considerable detail, it will be understood that the description thereof is intended to be illustrative, rather than restrictive, as many details may be modified or changed without departing from the spirit or scope of my invention. Accordingly, I do not desire to be restricted to the exact structure described.

I claim:

1. An intermediate support for a tilt rail comprising a fixed bracket, a roller mounted in said bracket to rotate in a plane transverse of the tilt rail to be supported, a clamp frictionally secured to said tilt rail beneath said roller, a plurality of ears projecting outwardly from said clamp, and a chain extending around the periphery of

said roller, the ends of said chain being secured to said clamp by engagement with said ears.

2. An intermediate support for a tilt rail comprising a fixed bracket, a roller mounted in said bracket to rotate in a plane transverse of the tilt rail to be supported, a snap-on clamp frictionally secured to said tilt rail beneath said roller, said clamp comprising a base member adapted to be positioned against the lower face of the tilt rail and legs adapted to be positioned on opposite sides of the tilt rail with the free ends of the legs extending slightly above the top face of the tilt rail, the free ends of said legs being recessed, and a chain extending around the periphery of said roller and through said recesses and having its ends secured to the base of the clamp.

BELA B. JUNKUNC.
